Attorney

UNITED STATES PATENT OFFICE.

HERMAN O. R. WINKELMAN, OF BALTIMORE, MARYLAND.

COLLAR.

Application filed July 25, 1925. Serial No. 46,000.

To all whom it may concern:

Be it known that I, HERMAN O. R. WINKELMAN, a citizen of the United States, residing at Baltimore city, State of Maryland, have invented certain new and useful Improvements in Collars, of which the following is a specification.

This invention relates to collars.

It is well understood that many persons have necks which are unduly enlarged making the wearing of the usual type of collar uncomfortable and frequently preventing the closing of the neck band of the shirt. For instance, a man may have a goiter so that he cannot button the neck band of his shirt.

One important object of this invention is to provide an improved form of collar which, while appearing like the ordinary collar, may be worn with a shirt having the neck band open.

Again, the neck under such conditions is often sensitive.

A second important object of the invention is to provide an improved collar wherein no buttons will contact with the skin of the neck.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a front view of the upper part of a shirt showing the improved collar attached thereto.

Figure 2 is a view showing the inner face of the collar in flat position.

Figure 3 is a front view of the upper portion of a shirt arranged to receive this collar, the collar being removed.

Figure 4 is a vertical section through the collar.

In carrying out this invention there is provided a collar of the usual turn down

type having a body 10 and band 11. At each end of the band is provided a button hole 12 as in ordinary collars but the collar differs from that commonly used in that the band is intended to fit inside the neck band of the shirt. To that end the band is provided, on the side which lies next the body in folded position, with a series of tabs 13 sewed thereon and each having a button hole 14 for the reception of the base of an ordinary collar button. One of these tabs is secured at the back center while the others are secured in spaced relation to the ends. Thus the collar has five button holes instead of the usual three.

The shirt may be made with a special band 15 to correspond to the collar size and provided with a back button hole 16, front button holes 17 and side button holes 18 corresponding in position to the button holes in the collar.

In securing the collar to the shirt buttons are passed through the button holes 14 and through the button holes 16 and 18. Then a single button may be passed through the holes 12 and 17.

The collar may be worn with an ordinary shirt by opening the collar band and securing the ends of the band by collar buttons to the lateral tabs 13, the ends of the collar being allowed to come down in front of the gap in the shirt and being secured together by a collar button.

Thus an abnormally large collar may be worn without markedly destroying the appearance of the shirt.

There has thus been provided a simple and efficient device of the kind described and for the purpose specified.

Having thus described the invention, what is claimed as new is:

A collar having a band provided with button holes at its ends, and tabs secured to said collar at the rear and side portions of the band and on the outer face of the band, said tabs being provided with button holes.

In testimony whereof I affix my signature.

HERMAN O. R. WINKELMAN.
